UNITED STATES PATENT OFFICE

2,417,471

LIFTING DEVICE FOR SLIDING DOORS

Frank Ditchfield, Cleveland, Ohio, assignor to
The Youngstown Steel Door Company, Cleve-
land, Ohio, a corporation of Ohio

Application December 31, 1943, Serial No. 516,331

11 Claims. (Cl. 16—99)

1

This invention relates to lifting devices for sliding doors.

It is an object of this invention to provide lifting devices for sliding doors which shall be economical and designed for application to the structures upon which the sliding doors are mounted.

A further object is to provide door lifting devices applicable to railway cars of varying widths without encroaching upon the tunnel clearance lines.

A further object is to provide lifting devices for sliding doors embodying balls adapted to support the doors for opening and closing movements.

A further object is to provide lifting devices for sliding doors which shall embody supporting balls and a track substantially shorter than the usual track for sliding doors.

A further object is to provide lifting devices for sliding doors which shall embody supporting balls and a track supported from the structures upon which the doors are mounted by substantially fewer brackets than are usually employed.

A further object is to provide lifting devices for sliding doors embodying anti-friction supporting means which shall normally be disengaged from the doors and movable upward to engage and lift the doors and support them for easy rolling movement.

It is a further object to provide lifting devices for sliding doors embodying balls and tracks upon which the balls are adapted to roll, wherein the balls are normally disengaged from the doors and the tracks are movable upward to engage the balls with and raise the doors.

A further object is to provide lifting devices of the character set forth immediately above wherein the doors and the tracks cooperate to maintain the balls in pre-determined positions when the doors are open and closed.

A further object is to provide lifting devices for normally frictionally supported doors embodying anti-friction means disengaged from the doors when the latter are frictionally supported and engaged with the doors to lift and support them above their frictional support for rolling movement, the frictional support for the doors being independent of the support for the anti-friction means and cooperating with the doors to provide effective sealing means.

Other objects of the invention will become clear as the description thereof proceeds.

In the drawings forming part of this specification:

Fig. 1 is a fragmentary elevation illustrating 55

2

portions of a railway house car, a sliding door mounted thereon and a lifting device embodying the instant invention.

Fig. 2 is a vertical section taken on line 2—2 of Fig. 1.

Fig. 3 is a vertical section taken on line 3—3 of Fig. 1 but showing the door in raised position.

Fig. 4 is a vertical section taken on line 4—4 of Fig. 1.

Fig. 5 is a plan view of one of the brackets and rollers utilized in the instant invention.

Fig. 6 is a front elevation of one of the brackets and rollers of the instant invention and a portion of a track supported by the bracket, a part of the track being broken away in order to more clearly illustrate the construction thereof.

Referring to the drawing, the preferred embodiment of the invention illustrated is shown applied to a railway house car whose underframe 20 embodies an angle side sill 10 reinforced by means of a bulb angle 11 whose horizontal leg 12 is secured in any desired manner to the horizontal leg 13 of the side sill. A door opening is provided in the side 14 of the car and is defined in part by means of the front door post 15 and the rear door post 16. The floor of the car is shown at 17 and is adapted to be supported upon the horizontal leg 13 of the side sill as more clearly illustrated in Figs. 2 and 3 of the drawings. A threshold plate 18 lies upon the floor 17 and extends outwardly therefrom and across the upstanding leg 19 of the side sill to the outer face of the front and rear door posts. The threshold plate 18 is flanged as indicated at 20 and is supported beyond the side sill within the door opening by means of a channel-shaped member 21 whose web 22 is secured as by means of rivets 23 to the upstanding leg 19 of the side sill. The upper horizontal leg 24 of the threshold support 20 is disposed within the space provided by the return flange 20 of the threshold plate 18 in abutment with the threshold plate. The lower horizontal leg 25 is so disposed as to function in a manner hereinafter described.

The lifting device of the instant invention embodies a plurality of spaced brackets 26. As clearly shown in Fig. 1 of the drawings, the instant invention permits the use of only four brackets, a number which is substantially fewer than the seven brackets customarily required for lifting devices of other designs. As shown, the brackets are preferably constructed of plates. Each bracket comprises an outer substantially channel-shaped plate member having an outwardly disposed web 27 and inwardly directed

walls 28 and 29. These walls are turned outwardly in opposite directions to provide attaching flanges 30 and 31 by means of which the bracket is secured to the side sill reinforcement 11 as by means of rivets 32 and 33. Each bracket includes an inner substantially channel-shaped plate member 34 having a web 35 spaced inwardly from the web 27 and inwardly directed flanges 36 and 37 secured as by means of rivets 38 and 39 to the inwardly directed walls 28 and 29 of the bracket member 26. A roller 40 is disposed within the space between the webs 27 and 35 and is rotatably supported by means of a pin 41 fastened in said webs.

The brackets 26 are adapted to support a track 42 which, as more clearly shown in Figs. 2 and 3 of the drawings, is channel shaped in section. The track 42 embodies a web 43 disposed upon the rollers 40 which extend above and below the webs 27 and 35 of the brackets and inner and outer legs 44 and 45 which lie on opposite sides of the rollers. Secured to the underside of the web 43 of the track adjacent to each of the rollers 40 of the brackets are a plurality of members 46 the forward ends 47 of which are wedge-shaped for a purpose which will hereinafter appear. It is to be observed that the track terminates a substantial distance from the front stop 48 of the door and from the back stop 49 and is substantially shorter than the track employed with lifting devices of other designs. Stop members 50 and 51 are secured to and extend upwardly above the track adjacent to the ends thereof, as more clearly shown in Fig. 1 of the drawings.

The track 42 supports a plurality of balls 52 and 53 maintained in spaced relationship by means of a ball carriage 54. It is preferred that the ball 52 be disposed somewhat less than half the width of the door, which the balls are adapted to support, from the rear edge thereof when the door is closed so that free rolling movement of the door will be obtained throughout its entire travel.

A sliding door is shown associated with the lifting device of the instant invention. This door may be of any desired construction but as is illustrated embodies a metallic panel 55 reinforced by means of a plurality of horizontal corrugations 56 which merge at their ends into vertical corrugations 57 and 58. Along its lower margin the door is reinforced by means of a Z-shaped member 59 whose upstanding leg 60 is overlapped by and secured to the panel 55 as by means of rivets 61. The web 62 of the Z-shaped reinforcing member extends outwardly from the leg 60. The outer leg 63 of the Z-shaped reinforcing member extends downwardly from the outer edge of the web 62 in spaced relationship with the downwardly extending flange 64 of a T-shaped reinforcing member 65 whose upstanding flange 66 is secured by means of the rivets 61 to the leg 60 of the Z-shaped reinforcing member 59 and to the panel 55. The stem 67 of the T-shaped reinforcing member 65 extends inwardly between the upper and lower horizontal legs 24 and 25 of the threshold supporting channel 21. As more clearly shown in Figs. 2 and 3 of the drawings, the downwardly extending leg 63 of the Z-shaped reinforcing member 59 and the downwardly extending flange 64 of the T-shaped reinforcing member 65 lie on opposite sides of the track 42 and the leg 63, flange 64 and web 62 cooperate to provide a runway on the door for the balls 52 and 53. Stop members 68 and 69 are secured to and extend downwardly from the door reinforcing

members 59 and 65 adjacent to the vertical edges of the door. This securement may be effected by means of welding, as shown in Figs. 2 and 3 of the drawings.

Doors of the lift type are normally frictionally supported in their lowered position. Such support is obtained by the instant invention, as more clearly shown in Fig. 2 of the drawings, by means of the stem 67 of the T-shaped reinforcing member 65 which rests upon the lower leg 25 of the channel threshold plate support. Moreover, the described association between the elements 67 and 25 provides an efficient seal for the bottom of the door, thereby preventing the ingress of rain, snow, dust, cinders and the like, into the car. With further reference to Fig. 2 of the drawings, it is to be observed that the frictional support of the door upon the threshold plate support positions the web 62 of the Z-shaped reinforcing member 59 above the top of the balls 52 and 53 so that the latter are relieved of the weight of the door. Similarly, the door track and the brackets and rollers carried thereby do not bear any portion of the weight of the door.

When the door is frictionally supported and is in the position shown in Fig. 1 of the drawings, it will be apparent that the instant invention provides means whereby the balls are maintained in the position shown in this figure. This is accomplished by the forward stop 50 carried by the track and the rear stop 69 carried by the door. The balls and their spacer are disposed between these stops so that shifting of the balls and spacer either forwardly or rearwardly is prevented.

In order to move the door to its open position the track 42 is shifted forwardly and upwardly so that the balls 52 and 53 are moved upward into engagement with the web 62 of the Z-shaped reinforcing member 59 and then upon continued upward movement of the track and the balls, the door is raised so as to transfer the weight of the door from the threshold supporting member 21 to the balls. Movement of the track 42 is obtained by means of a lever 70 pivoted at its lower end, as indicated at 71, to a bracket 72 fastened to the side sill reinforcing angle 11 and by a link 73 whose ends are pivotally connected to an intermediate portion of the lever 70 and to the adjacent end of the track as indicated at 74 and 75. During the movement imparted to the track by means of the lever 70 and the link 73, the wedge-shaped ends 47 of the members 46 secured to the underside of the web of the track 42 engage the rollers 40 and ride upwardly upon the rollers, thereby lifting the track and the balls supported thereby upwardly. This movement of the track and the balls is continued until the frictional engagement between the door and the threshold plate support is broken and the door 60 supported upon the balls 52 and 53. The door may then readily be moved to its open position upon the balls. In this position, it will be apparent that shifting of the balls and the ball spacer is prevented by the stop member 51 on the track and the stop member 68 on the door between which the balls and spacer are confined. During the opening movement of the door, the stop 68 must pass the stop 50 and the stop 68 is accordingly terminated above the stop 50.

The channel-shaped threshold plate support lies entirely within the door opening. In order to provide for frictional support of the door when it is in open position an angle member 76 extending from the rear of the door opening to the front 75 stop is secured to the upstanding leg 19 of the

side sill 13 in such position that the horizontal leg 71 of the angle member 16 is aligned with and provides an extension of the lower leg 25 of the threshold support.

By virtue of the instant invention, the door and lifting device can be maintained within the most critical tunnel clearance diagram so that the lift fixture is applicable to all railway house cars irrespective of their width.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A lifting device for frictionally supported sliding doors of railway cars comprising a plurality of brackets adapted to be secured to a railway car, rollers supported by said brackets, a track supported upon said rollers, operating means adapted to impart longitudinal movement to said track upon said rollers, members secured to said track and engageable with said rollers during longitudinal movement of said track to impart upward movement thereto, and spaced anti-friction means carried by said track in spaced relationship to a door, said anti-friction means being movable upward by said track to engage and lift said door and also longitudinally relative to said track and door to support said door during opening and closing movements.

2. A lifting device for frictionally supported sliding doors of railway cars comprising supporting means adapted to be secured to a railway car, a track supported upon said supporting means, operating means adapted to impart longitudinal movement to said track upon said supporting means, members secured to said track and engageable with said supporting means during longitudinal movement of said track to impart upward movement thereto, and spaced anti-friction means carried by said track in spaced relationship to a door, said anti-friction means being movable upward by said track to engage and lift said door and also longitudinally relative to said track and door to support said door during opening and closing movements.

3. A lifting device for frictionally supported sliding doors of railway cars comprising supporting means adapted to be secured to a railway car, a track supported upon said supporting means, operating means adapted to impart longitudinal movement to said track, members secured to said track and engageable with said supporting means during longitudinal movement of said track to impart upward movement thereto, and spaced anti-friction means carried by said track in spaced relationship to a door, said anti-friction means being movable upward by said track to engage and lift said door and also longitudinally relative to said track and door to support said door during opening and closing movements, the forward end of said track terminating approximately midway between the vertical edges of said door when said door is closed, and the rear end of said track terminating approximately midway between the vertical edges of said door when said door is open.

4. A lifting device for frictionally supported sliding doors of railway cars comprising supporting means adapted to be secured to a railway car, a track supported upon said supporting means, operating means adapted to impart lon-

gitudinal movement to said track upon said supporting means, members secured to said track and engageable with said supporting means during longitudinal movement of said track to impart upward movement thereto, spaced anti-friction means carried by said track in spaced relationship to a door, said anti-friction means being movable upward by said track to engage and lift said door and also longitudinally relative to said track and door to support said door during opening and closing movements, the forward end of said track terminating approximately midway between the vertical edges of said door when said door is closed, and the rear end of said track terminating approximately midway between the vertical edges of said door when said door is open and means on said car adapted to frictionally support said door when said track and anti-friction means are lowered.

5. A lifting device for frictionally supported sliding doors of railway cars comprising supporting means adapted to be secured to a railway car, a track supported upon said supporting means, operating means adapted to impart longitudinal movement to said track upon said supporting means, members secured to said track and engageable with said supporting means during longitudinal movement of said track to impart upward movement thereto, anti-friction means carried by said track in spaced relationship to a door, said anti-friction means being movable upward by said track to engage and lift said door and also longitudinally relative to said track and door to support said door during opening and closing movements, a carriage maintaining said anti-friction means in spaced relation, front and rear stop members for said carriage extending upwardly from said track, front and rear stop members for said carriage depending from said door, the front track stop member and the rear door stop member cooperating to prevent displacing of said anti-friction means and carriage when said door is closed, the front door stop member and the rear track stop member cooperating to prevent displacement of said anti-friction means and carriage when said door is open.

6. A lifting device for frictionally supported sliding doors of railway cars comprising a plurality of brackets adapted to be secured to a railway car, rollers supported by said brackets, a channel-shaped track having a web engaging said rollers and legs lying on opposite sides of said rollers, operating means adapted to impart longitudinal movement to said track upon said rollers, members having wedge-shaped ends secured to the underside of said web adjacent to said rollers and engageable with said rollers during longitudinal movement of said track to impart upward movement thereto, and spaced anti-friction means carried by said track in spaced relationship to a door, said anti-friction means being movable upward by said track to engage and lift said door and also longitudinally relative to said track and door to support said door during opening and closing movements.

7. A lifting device for frictionally supported sliding doors of railway cars comprising supporting means adapted to be secured to a railway car, a track supported upon said supporting means, operating means adapted to impart longitudinal movement to said track upon said supporting means, members secured to said track and engageable with said supporting means during longitudinal movement of said track to im-

part upward movement thereto, anti-friction means carried by said track in spaced relationship to a door, a carriage maintaining said anti-friction means in spaced relation, said anti-friction means being movable upward by said track to engage and lift said door and also longitudinally relative to said track and door to support said door during opening and closing movements, the forward end of said track terminating approximately midway between the vertical edges of said door when said door is closed, and the rear end of said track terminating approximately midway between the vertical edges of said door when said door is open, stop members for said carriage extending upward from said track adjacent to the ends thereof, and stop members for said carriage depending from said door adjacent to the vertical edges thereof.

3. In a railway house car having a sliding door, a track for said door, means secured to said car for supporting said track, anti-friction means on said track movable relative to said door and track for supporting said door during opening and closing movements, a carriage maintaining said anti-friction means in spaced relation, the forward end of said track terminating approximately midway between the vertical edges of said door when said door is closed, and the rear end of said track terminating approximately midway between the vertical edges of said door when said door is open, stop members for said carriage on and adjacent to the ends of said track, and stop members for said carriage depending from said door adjacent to the vertical edges thereof.

9. A lifting device for frictionally supported sliding doors of railway cars having a threshold plate and threshold plate supporting means comprising supporting means adapted to be secured to a railway car, a track supported upon said supporting means, operating means adapted to impart longitudinal movement to said track, members secured to said track and engageable with said supporting means during longitudinal movement of said track to impart upward movement thereto, spaced anti-friction means carried by said track in spaced relationship to a door, said anti-friction means being movable upward by said track to engage and lift said door and also longitudinally relative to said track and door to support said door during opening and closing movements, the forward end of said track termi-

5 nating approximately midway between the vertical edges of said door when said door is closed, and the rear end of said track terminating approximately midway between the vertical edges of said door when said door is open, said threshold plate supporting means engaging and frictionally supporting said door when said track and anti-friction means are lowered, said threshold plate supporting means extending between and sealing the space between said door and said car.

10. In a railway house car having a sliding door, a track for said door, means secured to said car for supporting said track, spaced anti-friction means on said track movable relative to said door and track for supporting said door during opening and closing movements, a carriage maintaining said anti-friction means in spaced relation, stop members for said carriage carried by said track, and stop members for said carriage depending from said door adjacent to the vertical edges thereof.

15 11. A lifting device for frictionally supported sliding doors of railway cars comprising supporting means adapted to be secured to a railway car, a track supported upon said supporting means, operating means adapted to impart longitudinal movement to said track upon said supporting means, members secured to said track and engageable with said supporting means during longitudinal movement of said track to impart upward movement thereto, spaced anti-friction means carried by said track in spaced relationship to a door, said anti-friction means being movable upward by said track to engage and lift said door and also longitudinally relative to said track and door to support said door during opening and closing movements, a carriage maintaining said anti-friction means in spaced relation, stop members for said carriage on said track, and stop members for said carriage depending from said door adjacent to the vertical edges thereof.
